FLORAL-VASE OR THE LIKE

Edwin K. Kaelke, Macomb, Ill., assignor to The Haeger Potteries, Inc., Dundee, Ill., a corporation of Illinois

Filed Apr. 21, 1964, Ser. No. 79,639

Term of patent 14 years

(Cl. D29—28)

Fig. 1

Fig. 3

FIG. 1 is a side elevational view of a floral vase or the like embodying my new design;

FIG. 2 is a top plan view thereof; and

FIG. 3 is a bottom plan view thereof.

I claim:

The ornamental design for a floral vase or the like, substantially as shown.
